US0D1036936S

(12) **United States Design Patent** (10) **Patent No.:** **US D1,036,936 S**
(45) **Date of Patent:** **** Jul. 30, 2024**

(54) **BOTTLE**

(71) Applicant: **YETI Coolers, LLC**, Austin, TX (US)

(72) Inventors: **Dustin R. Bullock**, Austin, TX (US); **Colin Darling**, Austin, TX (US); **Evan Goldberg**, Austin, TX (US); **Hector Barea**, Austin, TX (US)

(73) Assignee: **YETI Coolers, LLC**, Austin, TX (US)

(**) Term: **15 Years**

(21) Appl. No.: **29/813,038**

(22) Filed: **Oct. 26, 2021**

(51) LOC (14) Cl. **07-01**

(52) U.S. Cl.

USPC **D7/510; D7/511**

(58) **Field of Classification Search**

USPC .... Primary Examiner — Michael C Stout

Assistant Examiner — Tia Ruth-Renee Polidori

(74) Attorney, Agent, or Firm — Banner & Witcoff, Ltd.

(57) **CLAIM**

The ornamental design for a bottle, as shown and described.

DESCRIPTION

FIG. 1 is a front, right, top perspective view of a bottle showing our new design;

FIG. 2 is a rear, right, bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front, right, top perspective view thereof, shown separated for clarity of disclosure;

FIG. 10 is a rear, right, bottom perspective view thereof;

FIG. 11 is a front view thereof;

FIG. 12 is a rear view thereof;

FIG. 13 is a right side view thereof; and,

FIG. 14 is a left side view thereof.

The portions of the bottle shown in broken lines form no part of the claimed design.

1 Claim, 9 Drawing Sheets
